UNITED STATES PATENT OFFICE

102,649

DESIGN FOR AN ELECTRIC RANGE CONTROL PANEL

John H. Grayson and George Greenamyer,
Lynwood, Calif.

Application September 29, 1936, Serial No. 65,067

Term of patent 3½ years

To all whom it may concern:

Be it known that we, John H. Grayson and George Greenamyer, citizens of the United States, and residents of Lynwood, in the county of Los Angeles and State of California, have invented a new, original, and ornamental Design for an Electric Range Control Panel, of which the following is a specification, reference being had to the accompanying drawing, forming part thereof.

Fig. 1 is a front elevation of an electric range control panel embodying the invention, and
Fig. 2 is a plan view thereof.

I claim:

The ornamental design for an electric range control panel, as shown.

JOHN H. GRAYSON.
GEORGE GREENAMYER.
